Primary Examiner — Cynthia Ramirez(74) *Attorney, Agent, or Firm* — Polson Intellectual Property Law, PC; Margaret Polson(57) **CLAIM**

The ornamental design for a cart, as shown and described.

DESCRIPTION

FIG. 1 is a front isometric view of a cart showing my new design.

FIG. 2 is a left side elevation view of FIG. 1.

FIG. 3 is a right side elevation view of FIG. 1.

FIG. 4 is a front side elevation view of FIG. 1.

FIG. 5 is a back side elevation view of FIG. 1.

FIG. 6 is a top plan view of FIG. 1.

FIG. 7 is a bottom plan view of FIG. 1; and,

FIG. 8 is a side elevation view of the left side with a second cart nested to the first cart, the second cart being shown in broken lines, it being understood second cart is identical to all other views of this embodiment other than being shown in the nested position.

The features shown in broken lines in the drawing depict environmental subject matter only and form no part of the claimed design.

1 Claim, 7 Drawing Sheets(56)
